UNITED STATES PATENT OFFICE

JESSE B. HAWLEY, OF WILMETTE, ILLINOIS, AND RALPH H. TOWNSEND, OF MOUNT VERNON, NEW YORK, ASSIGNEES, BY MESNE ASSIGNMENTS, TO UNITED REPRODUCERS CORPORATION, OF ST. CHARLES, ILLINOIS, A CORPORATION OF NEW JERSEY

SOUND AMPLIFIER

Application filed April 19, 1924. Serial No. 707,578.

The present invention relates to sound amplifiers, such as those used in talking machines, radio apparatus and like and similar devices.

Among the objects of the invention is to provide a novel device for amplifying sound free from distortion, false and discordant tones and incorrect timbre, metallic resonance, and the like but which will reproduce sound or sound waves as nearly true to the original or created sound as possible; to provide for reflecting the emitted reproduced sound waves for purifying the tones and timbre; to successively reflect such waves; to provide for adjusting the relation of the reflectors with respect to each other and the relation of the reflectors with respect to the reproducing device, such as a telephonic receiving unit or phonographic sound box or the like; to provide a reflector with a substantially caustic surface for efficiently reflecting the sound conducted to it from the reproducer; to provide a reflector of concave or hollow form and of substantially ellipsoidal form with preferably a smooth reflecting surface; to provide the reflectors of material varying in thickness or density from the central or axial or nodal portions thereof toward the outer or marginal portions thereof; to provide a pair of reflectors having their reflecting portions directed toward each other such that the sound incident upon one may be reflected to the other and the latter to reflect the sound by or through the former which may be spaced from the other reflector or provided with openings for the passage of the sound from the device; and to provide such other objects, advantages and capabilities as will later appear and are inherently possessed by the invention.

In the drawing showing an illustrative embodiment of the invention, Fig. 1 is a perspective view, with fragmentary sections, of a device constructed in accordance with the invention; Fig. 2 is a vertical axial sectional view; and, Fig. 3 is a front elevational view, with part broken away.

Referring more particularly to the drawing, the device is shown as comprising a body

member or reflector 1 of generally concave shape and of ellipsoidal form and provided at the front thereof with an opening 2 acting as the discharge outlet for the sound. At the rear of the body is provided a small opening 55 in which is suitably supported a sound conducting member or tube 3 which preferably diverges toward the front of the device and has its forward end portion 4 open to discharge or emit sound waves against a reflector 5. The latter is provided with a substantially or approximately caustic surface and substantially in axial alignment with the tube 3. The reflector 5 has rearwardly extending flared portions 7 so as to form a sort of diverging or bell-shaped body for directing the sound waves rearwardly toward the body 1. The portion 7 of the reflector 5 extends radially with curved or reflexed marginal portions 8 which are preferably provided with a series of apertures 9, as clearly shown in the drawing. At the front of the body 1 is suitably mounted a grid or like device 10 provided with a suitable number of openings 11 through which the sound passes from the device into the air space of a room or the like.

Both the body member 1, which acts as a reflector, and the reflector 5 are preferably made with the material thereof tapering 80 from the central portions thereof toward the margins thereof so that their resonance may be improved to obtain the desired quality of tones being amplified and transmitted from the reproducing device to the hearers. The 85 tube 3, body 1 and reflector 5 may be made of any suitable material, such as fibrous substance, papier-mâché, paper pulp, or even wood or metal as desired and as the conditions may dictate. The body member 1 is preferably provided with a supporting base portion 12 for the purpose of supporting the device in upright position with the axis thereof in substantially horizontal position. A reproducing device 13 may be secured to the 95 tube 3 in any suitable manner. Preferably the reproducer, which may be a talking machine sound box or a telephonic receiver for radio apparatus or the like, is preferably formed with a neck 14 suitably apertured to 100

receive the rear end of the tube 3 and externally threaded to fit in a bushing or ferrule 15 connected to the body 1 in the aperture provided in the rear part thereof, as clearly shown in Fig. 2 of the drawing. The purpose of the threads is that the tube 3 together with the reproducer, may be adjusted axially to and from the reflector 5.

In like manner the grid 10 may be adjusted 10 in the outlet of the member 1. Within this outlet is provided an annular member 16, preferably of metal although other suitable material may be used, and having internal threads engaging with a threaded portion or 15 flange 17 of the grid. This flanged portion may be, if desired, an annular member fitted over the rim or periphery of the grid or the threads may be made directly into the grid itself, if the material thereof will admit it. 20 The reflector 5 is preferably secured or connected to the central portion of the grid by suitable fastening elements 18 as clearly shown in the drawing. It will thus be seen from the above described construction that 25 the grid together with the reflector 5 may be adjusted axially by a turning of the grid and the reflector so that the threads of the member 17 will ride in the threads of the member 16. From this it will be apparent that either the 30 reflector 5 or the tube 3 may be adjusted with respect to each other or both adjusted together. In this way the distance of reflection between the reflectors 1 and 5 may be varied at will to vary the amplification of the sound 35 and to improve the quality of the tones being amplified, and to also vary the distance between the reflecting surface 6 of the reflector 5 and the discharge outlet 4 of the tube 3.

In operation the reproducer 13 will set up 40 the vibration of the column of air in the tube 13 producing sound waves which are emitted through the opening or discharge outlet 4 of the tube 3 and upon the reflecting surface 6 of the reflector 5. From this surface the sound 45 is reflected rearwardly through the flared portion 7 of the reflector and directed against the inner surface 19 of the body member 1. From this surface the sound may be reflected 50 through the opening 9 and also around the space between the rim or margin of the reflector 5 and the inner surface of the body portion 1. The sound will then proceed 55 through the openings 11 of the grid and to the exterior of the device in amplified form. The inner surface 19 of the reflector 1 is preferably smooth.

While we have herein described and upon the drawing shown a preferred embodiment of the invention, it is to be understood that it 60 is not limited to the particular details, arrangement of parts and construction described and shown, but that other details, arrangements of parts and constructions are comprehended by the invention without de- 65 parting from the spirit thereof.

Having thus described our invention, we claim:

1. A sound amplifier comprising an approximately semi-ellipsoidal hollow body having an opening at one side thereof, means 70 for directing sound waves against the inner surface of said body whereby the sound waves may be reflected and amplified.

2. A sound amplifier comprising an approximately semi-ellipsoidal hollow body 75 having an opening at one side thereof, a reflector within said body and capable of directing sound waves to the inner surface of said body whereby the sound waves may be reflected and amplified. 80

3. A sound amplifier comprising an approximately semi-ellipsoidal hollow body having an opening at one side thereof, a reflector within said body and capable of directing sound waves to the inner surface 85 of said body whereby the sound waves may be reflected and amplified, and means for directing sound waves against said reflector to be transmitted therefrom to said body.

4. A sound amplifier comprising an approximately semi-ellipsoidal hollow body having an opening at one side thereof, a sound conveying tube leading into said body, means for directing the sound emitted from said tube to said body for reflection and 90 amplification thereof, and means adjustably mounted in said body and connected to said sound directing means for adjusting its position. 95

5. A sound amplifier comprising a hollow body member having a sound outlet opening at one side thereof, a sound conveying tube extending into said body member through the other side thereof, a reflecting member for reflecting the sounds emitted from the 100 tube to the inner surface of the body member remote from said outlet opening whereby the sound is reflected by the body member and emitted through said outlet opening in amplified and improved condition, and means adjustably mounted in said body and connected to said sound directing means for adjusting its position. 105

6. A sound amplifier comprising a hollow body member having a sound outlet opening at one side thereof, a sound conveying tube extending into said body member through the other side thereof, a bell-shaped reflector opposite said tube and extending inwardly 110 toward said other side of the body member for reflecting sound thereto, the inner extending end of said reflector being spaced from said body member for providing an outlet passage for the sound reflected from said body member. 115

7. A sound amplifier comprising a hollow body member having a sound outlet opening at one side thereof, a sound conveying tube extending into said body member through the other side thereof, a flaring reflector 120 125 130

- opposite the inner end of said tube for reflecting sound to the inner surface of said body member, said reflector having a marginal portion provided with apertures for 5 affording passage of the sound reflected from said body member.
8. A sound amplifier comprising a hollow body having a sound outlet, a sound conveying passage extending into said body and 10 having a sound discharging opening, a reflector in said body and located opposite said opening, said reflector having means cooperating with said body member and said reflector for adjustably supporting the reflector in the body.
9. A sound amplifier comprising a hollow body having a sound outlet, a sound conveying passage extending into said body and having a sound discharging opening, a reflector in said body and located opposite said opening, and means connected to the reflector and to the body for adjustably supporting the reflector therein and whereby the reflector may be moved to and from said 25 opening.
10. A sound amplifier comprising a hollow body having a sound outlet, a sound conveying passage extending into said body and having a sound discharging opening, a reflector in said body and located opposite said opening, a supporting member adjustably supported in the outlet of the body and secured to said reflector whereby the space between said reflector and the opening of the 35 passage may be varied when the supporting member is adjusted.
11. A sound amplifier comprising a hollow body having a sound outlet, a sound conveying passage extending into said body and 40 having a sound discharging opening, a reflector in said body and located opposite said opening, a grid adjustably mounted in the outlet of said body, said reflector being secured to said grid whereby it may be adjusted to and from said passage for varying the sound.
12. A sound amplifier comprising a hollow body having a sound outlet, a sound conveying passage extending into said body and 50 having a sound discharging opening, a reflector in said body and located opposite said opening, said reflector and said passage being adjustably supported in said body whereby either or both may be adjusted to and from 55 each other as desired.
13. A sound amplifier comprising a hollow body having a forward outlet for discharge of amplified sound, and provided with a rim about said outlet, a grid adjustably connected to said rim, a sound reflector connected to said grid and movable therewith whereby the distance between the rear of said body and said reflector may be varied at will.
14. A sound amplifier comprising a hollow 65 body having a forward outlet for discharge
- of amplified sound and provided with an aperture in the rear wall thereof, a sound conveying tube extending through said aperture and into said body, and means for adjustably connecting the tube to said body in said aperture whereby the discharge end of the tube may be adjusted with reference to the inner rear surface of the body.
15. In a sound amplifier having a hollow body provided with a sound outlet and means for conducting sound into said body, a reflector having a caustic surface and flaring walls for reflecting the sound emitted from said conducting means into said body.
16. In a sound amplifier having a hollow body provided with a sound outlet and means for conducting sound into said body, a reflector having a caustic surface and flaring walls, provided with reflexly curved marginal portions.
17. In a sound amplifier having a hollow body provided with a sound outlet and means for conducting sound into said body, a reflector having a caustic surface and flaring walls provided with apertured marginal portions.
18. In a sound amplifier having a hollow body provided with a sound outlet and means for conducting sound into said body, a reflector having a caustic surface and flaring walls provided with a reflexly curved margin in which is formed a series of apertures for the passage of amplified sound.
19. In a sound amplifier having a body member, and a reflector varying in thickness from the central portion thereof to the marginal portion thereof.
20. A sound reflector tapering in thickness from a nodal point toward the margin thereof.
- In witness whereof, we hereunto subscribe our names to this specification.
